UNITED STATES PATENT OFFICE.

HENRY D. CONE, OF STOCKBRIDGE, MASSACHUSETTS.

IMPROVEMENT IN THE MANUFACTURE OF RULED PAPER.

Specification forming part of Letters Patent No. **158,249**, dated December 29, 1874; application filed December 16, 1874.

To all whom it may concern:

Be it known that I, HENRY D. CONE, of Stockbridge, in the county of Berkshire and State of Massachusetts, have invented a new Improvement in the Manufacture of Ruled Paper; and I do hereby declare the following, when taken in connection with the accompanying drawings and the letters of reference marked thereon, to be a full, clear, and exact description of the same, and which drawings constitute part of this specification, and represent a transverse section or edge view of a sheet of this improved paper enlarged.

This invention relates to an improvement in "ruling" paper, the object being to produce paper with raised lines upon both surfaces; and it consists in writing-paper, the lines of which are embossed by or with an "ogee" pattern, which exposes a like face on opposite sides, as more fully hereinafter described.

In the drawing, *a* represents the lines upon

one surface, and *d* the lines upon the reverse surface, each raised upon its respective surface, and of convex form, the reverse presenting a corresponding concavity, the two lines presenting, in transverse section, a pattern known as ogee form, and as clearly seen in the illustration, and the lines upon the two surfaces of the paper being alike.

These lines are best produced by rolls, the surfaces of which are constructed with ribs and grooves corresponding to the said ogee pattern, but may be produced by other devices.

I claim—

As a new article of manufacture, writing-paper whereof the lines are embossed by or with an ogee pattern, which exposes a like face on opposite sides.

HY. D. CONE.
